HANDLING PALLET OR SKID ADAPTED FOR
LIFTING TRUCKS AND THE LIKEStanton K. McKim, Albion, Mich., assignor to
Union Steel Products Company, Albion, Mich.,
a corporation of Michigan

Application June 5, 1947, Serial No. 752,653

11 Claims. (Cl. 248—120)

1

This invention relates to material handling pallets or skids adapted for lifting trucks and the like.

The main objects of this invention are:

First, to provide a material handling pallet or skid which is well adapted for use with lifting trucks and which is light in weight and at the same time strong and rigid and capable of supporting and carrying relatively heavy loads.

Second, to provide a pallet or skid of this character which is fabricated entirely of metal.

Third, to provide a pallet or skid which may be engaged by the forks of a lifting truck with the forks presented thereto in various relations to the pallet or skid.

Objects relating to details and economies of the invention will appear from the description to follow. The invention is defined and pointed out in the claims.

A preferred embodiment of the invention is illustrated in the accompanying drawing, in which:

Fig. 1 is an inverted view of a material handling pallet or skid embodying the invention, only a portion of the grid-like top or platform being illustrated.

Fig. 2 is a fragmentary elevational view.

Fig. 3 is a fragmentary view in section on line 3—3 of Fig. 2.

Fig. 4 is a fragmentary plan view illustrating one of the steps of manufacture.

In the embodiment of the invention illustrated, the grid-like top or platform designated generally by the numeral 1 comprises an upper series of parallel wire or light rod slats 2 and a lower series of parallel wire or light rod slats 3. These are spot-welded at their crossing points as indicated at 4.

In the embodiment illustrated, the lower series of slats is of somewhat larger diameter than the intermediate slats of the series as is illustrated in Fig. 2. Spaced pairs of top bars 6 are disposed on the under sides of the grid or platform, these bars being welded to the under series of the slats and the bars of the pairs being substantially spaced as shown in Fig. 2.

Base bars 7, formed of sheet metal, are provided and disposed in spaced parallel relation transversely of the top bars 6. These base bars 7 are formed of sheet metal disposed horizontally flatwise and preferably have longitudinal stiffening ribs 8. The base bars 7 are turned upwardly at their ends as at 9 to facilitate sliding the pallet or skid on the frame or platform

2

and over another pallet or skid when they are stacked.

I provide a plurality of V-shaped leg members 10, also formed of sheet metal, the bights 11 of the leg members being fixedly secured to the base member 7 preferably by welding as indicated at 12. The upper ends of the legs of the leg members are welded to the top bars 6 as indicated at 13. Base rods 14 are arranged in the bights of the leg members and welded thereto as indicated at 15. The legs of the leg members are preferably longitudinally ribbed at 16 to stiffen the same.

With the parts thus arranged, there are openings between the legs to receive the forks of a lifting truck when presented thereto from any side of the pallet or skid or the forks may be engaged cornerwise should occasion require as a matter of convenience. The structure is formed entirely of sheet metal and at the same time may be formed of relatively light gauge stock and is strong and rigid and capable of sustaining heavy loads and severe usage.

In Fig. 4 I illustrate a desirable step in manufacture. In that illustration the leg units or members are shown in the flat. The top bars 6 are welded thereto and to the bottom bar or rod 14. This assembly of four parts is then manipulated to bring the leg members into V-shape and the top bar 6 welded to the platform. Thereafter, the base bars are welded to the aligned leg members.

I have illustrated and described my invention in an embodiment which I consider highly practical. I have not attempted to illustrate or describe various adaptations thereof which I contemplate as it is believed that this disclosure will enable those skilled in the art to embody or adapt the invention as may be desired. While the grid type of platform formed of wire or light rod stock is highly desirable it might be formed of sheet metal or even a wood top or platform might be employed.

Having thus described my invention, what I claim as new and desire to secure by Letters Patent, is:

1. In a materials handling pallet, the combination of a grid-like top comprising upper and lower series of parallel metal slats disposed with the slats of the series in crossing relation and fixedly connected at their crossing points, spaced pairs of top bars disposed in parallel relation on the under side of the top and transversely of the slats of the lower series and fixedly secured thereto, the bars of the pairs being laterally

spaced, a base comprising spaced parallel base bars of sheet metal disposed horizontally flatwise and in transverse relation to said top bars, sheet metal leg members comprising integral upwardly diverging legs disposed on and welded to the tops of said base bars, the upper ends of the legs being welded to the top bars of a pair, and base rods disposed transversely of the base bars in the bights of the leg members and welded thereto, the bights of the leg members being disposed between the base rods and the base bars, said base bars and legs having longitudinal reinforcing ribs struck therefrom, the ribs of the leg members terminating at their lower ends above the bights of the leg members, and the ribs of base bars extending between the bights of the leg members and terminating adjacent said bights.

2. In a materials handling pallet, the combination of a top comprising top bars disposed in parallel relation on the under side of the top, a base comprising spaced parallel base bars of sheet metal disposed horizontally flatwise and in transverse relation to said top bars, sheet metal leg members comprising integral upwardly diverging legs secured to said base bars, the upper ends of the legs being welded to the top bars, and base rods disposed transversely of the bars in the bights of the leg members and welded thereto, the bights of the leg members being disposed between the base rods and the base bars.

3. In a materials handling pallet, the combination of a top comprising upper and lower series of metal slats disposed with the slats of the series in crossing relation and fixedly connected at their crossing points, top bars disposed in parallel relation to the under side of the top and transversely of the slats of the lower series and fixedly secured thereto, a base comprising V-shaped sheet metal leg members, the upper ends of the leg members being secured to the top bars, and base rods disposed transversely of the base bars in the bights of the leg members and secured thereto, the bights of the leg members being disposed between the base rods and the base bars.

4. In a materials handling pallet, the combination of a top, a base comprising spaced base bars of sheet metal disposed horizontally flatwise, sheet metal leg members comprising integral upwardly diverging legs disposed on and fixedly secured to the said base bars, the upper ends of the bars being fixedly secured to the top, and base rods disposed transversely of the base bars in the bights of the leg members and fixedly secured thereto, the bights of the leg members being disposed between the base rods and the base bars.

5. In a materials handling pallet, the combination of a grid-like top comprising upper and lower series of parallel metal slats disposed with the slats of the series in crossing relation and fixedly connected at their crossing points, transversely spaced parallel sheet metal base members of substantial width disposed horizontally flatwise, V-shaped sheet metal leg members comprising upwardly diverging legs of a width corresponding substantially to the width of the base members disposed in longitudinally spaced relation upon said base members with their bights upon and welded thereto with corresponding legs in transversely aligned relation, leg top bars welded to the outer sides of corresponding transversely aligned legs of the leg mem-

bers at their upper ends and disposed transversely of the lower series of top slats and welded thereto, and transverse base members disposed within the bights of and fixedly connected to the lower ends of the leg members and constituting tie members for the transversely aligned leg members and the said first named base members.

6. In a materials handling pallet, the combination of a grid-like top comprising upper and lower series of parallel metal slats disposed with the slats of the series in crossing relation and fixedly connected at their crossing points, transversely spaced parallel sheet metal base members of substantial width disposed horizontally flatwise, sheet metal leg members comprising upwardly diverging integral vertically ribbed legs of a width corresponding substantially to the width of the base bars disposed in longitudinally spaced relation upon said base members and welded thereto, the corresponding legs of the leg members being in transversely aligned relation, leg top bars welded to the sides of corresponding transversely aligned legs of the leg members at their upper ends and disposed transversely of the lower series of top slats and welded thereto, the said base bars being longitudinally ribbed between the leg members, and transverse base members fixedly connected to the lower ends of the leg members and said first named base members and constituting transverse base members and tie members for the transversely aligned leg members and the said first named base members.

7. In a materials handling pallet, the combination of a top, transversely spaced parallel sheet metal base members of substantial width disposed horizontally flatwise, sheet metal leg members comprising upwardly diverging legs of a width corresponding substantially to the width of the base members disposed in longitudinally spaced relation upon said base members with corresponding legs of the leg members in transversely aligned relation, leg top bars welded to the sides of corresponding transversely aligned legs of the leg members at their upper ends and fixedly secured to the underside of the top, and transverse base members fixedly connected to the lower ends of the leg members and constituting transverse base members and tie members for the transversely aligned leg members and the said first named base members.

8. In a materials handling pallet, the combination of a metal top, transversely spaced parallel base members, sheet metal leg members comprising upwardly diverging legs of substantial width disposed in longitudinally spaced relation upon said base bars with corresponding legs of the leg members being in transversely aligned relation, leg top bars welded to the sides of corresponding transversely aligned legs of the leg members at their upper ends and fixedly secured to the underside of the top, and transverse base members fixedly connected to the lower ends of the leg members and constituting transverse base members and tie members for the transversely aligned leg members and the said first named base members.

9. In a materials handling pallet, the combination of a top, transversely spaced parallel sheet metal base members of substantial width disposed horizontally flatwise, V-shaped sheet metal leg members comprising upwardly diverging legs of a width corresponding substantially,

to the width of the base members disposed in longitudinally spaced relation upon said base bars with their bights upon and welded thereto and their upper ends fixedly connected to the top, and transverse base members fixedly connected to the lower ends of the leg members and to said first named base members and constituting tie members for the transversely aligned leg members and the said first named base members.

10. In a materials handling pallet, the combination of a top, transversely spaced parallel sheet metal base members disposed horizontally flatwise, sheet metal leg members comprising upwardly diverging legs disposed in longitudinally spaced relation to said base bars and fixedly connected thereto and their upper ends fixedly secured to the top with corresponding leg members in transversely aligned relation, and transverse base members fixedly connected to the lower ends of the leg members and said first named base members and constituting tie members for the transversely aligned leg members and the said first named base members.

11. In a materials handling pallet, the combination with a top, of spaced leg units each comprising V-shaped leg members of sheet metal of substantial width having upwardly diverging integral legs, corresponding legs being

disposed in alignment, leg top bars welded to the upper ends of corresponding aligned legs of the leg members and fixedly secured to the underside of the top with the leg units in transversely spaced relation, base members fixedly secured to the lower ends of the aligned leg members of the units, and base members of sheet metal of substantial width disposed horizontally flatwise and fixedly secured to corresponding leg members of the leg units and in crossed relation to said first named base members.
